(57) **CLAIM**

The ornamental design for a flying propeller, as shown and described.

DESCRIPTION

FIG. 1 is a perspective view of the flying propeller showing my new design;

FIG. 2 is a perspective view of my design shown in an environment of use;

FIG. 3 is a front elevation view thereof;

FIG. 4 is a rear elevation view thereof;

FIG. 5 is a right side view of my design;

FIG. 6 is a left side view of my design;

FIG. 7 is a top plan view of my design; and,

FIG. 8 is a bottom plan view of my design.

In the drawings, the broken lines depict environmental subject matter only and form no part of the claimed design.
